ORNAMENTAL JEWELRY STRUCTURE

Karl Fassnacht, Providence, R. I., assignor to
Speidel Corporation, Providence, R. I., a corpora-
tion of Rhode Island

Application February 10, 1936, Serial No. 63,178

3 Claims. (Cl. 40—140)

This invention relates to an ornamental jewelry structure, and more particularly to a device of this character having incorporated therein an initial display member adapted to display any desired initials and forming a relatively subsidiary portion of the ornamental structure.

One object of the invention is the provision of an initial display member as an element of rather than as the dominant feature of an ornamental jewelry structure, wherein the initial display member is of relatively small size and is suitably arranged to form a part of the ornamental structure.

Another object of the invention is the provision of an initial display member provided with a movable closure portion and having a supporting portion integrally united with the ornamental structure for receiving initial members and holding them in suitable display position between the movable closure portion and supporting portion of said initial display member.

A further object of the invention is the provision of a novel form of initial display member comprising a separate initial supporting plate and pivotally connected supporting and holding members adapted for the direct reception of the separate supporting plate and initial members and for holding them securely in position to provide for suitable display of the initial members.

Other objects and advantages of the invention relate to various improved details of construction and novel arrangements of the parts as will be more fully set forth in the detailed description to follow.

Referring to the drawing:—

Fig. 1 is a perspective view of an ornamental jewelry structure in the form of a pin and having incorporated therein an initial display member substantially integrally united with a portion of the ornamental structure.

Fig. 2 is a perspective view of another form of ornamental jewelry structure showing an initial display member secured thereto or formed integral therewith and arranged in a somewhat different manner than in the structure shown in Fig. 1.

Fig. 3 is a longitudinal sectional view through the initial display member and a portion of the ornamental jewelry structure shown in Fig. 1.

Fig. 4 is a transverse sectional view through the initial display member and a portion of the jewelry structure shown in Fig. 2.

Fig. 5 is a perspective view of the initial display member showing the separate initial supporting plate in position upon the supporting

member, and with the supporting and holding members in open position, and,

Fig. 6 is a disassembled view of the parts of the initial display member showing the supporting plate in separated relation with the hingedly connected holding and supporting members.

In the embodiment of the invention as illustrated in Fig. 1, 1 designates generally an ornamental jewelry structure in the form of an ornamental pin, the main portions of which may consist of one or more looped strands 2 suitably arranged to present an ornamental appearance and made up of a metal portion 3 and an ornamental portion 4 closely united therewith to provide a strand of a novel and ornamental character. The ornamental structure may be provided with a pin 5 pivotally mounted thereon, as at 6, and a catch 7 for receiving and holding the free end of the pin. An initial display member 8 is formed integral with or fixedly united to a portion 9 of the ornamental structure and is of a relatively small size as compared with the ornamental structure to provide an initial display means as an adjunct thereto. The initial display member comprises a supporting member 10 having opposed upstanding sides 11, and which may be provided with an opening 12 located substantially centrally thereof and between the upstanding sides 11. A separate supporting plate 14, which may or may not be provided with a central opening 15, is shaped to fit within the upstanding sides 11 and rest upon the supporting member 10. The separate supporting plate 14 is provided upon one side adjacent to a lateral edge thereof with a plurality of raised detents 17 for engagement with recesses 18 formed in the ends of initial members 19 to hold the initial members securely in spaced position upon the supporting plate 14. A holding member 20 is pivotally secured at one end to one end portion of the supporting member 10, as indicated at 22, and has an opening 23 formed therein which may conform substantially in size and location with the openings 12 and 15, when present, in the supporting member and separate supporting plate respectively. The lateral edges of the holding member 20 are adapted to lie partially or wholly within the upstanding sides 11 of the supporting member 10 in the closed positions of the parts, and the holding member 20 is provided with a somewhat resilient end lug 24 adapted to snap over and engage the end 25 of the supporting member 10, which end may be slightly beveled or inclined, to retain the holding member and sup-

porting plate 14 in the closed position.

Fig. 2 illustrates another form of ornamental jewelry structure in the form of a pin 26 having a supporting member 27 pivotally secured to a portion 28 of the ornamental structure, and a holding member 29 pivotally secured to the supporting member 27.

Fig. 3 illustrates a longitudinal sectional view through the initial display member 8 and a portion 30 of the ornamental structure.

Fig. 4 illustrates a transverse sectional view through the initial display member 8 and a portion 31 of the ornamental structure.

Fig. 5 illustrates a perspective view of the initial display member 8 showing the separate initial supporting plate 14 in position upon the supporting

member 10, and with the supporting and holding members in open position, and,

Fig. 6 illustrates a disassembled view of the parts of the initial display member showing the supporting plate 14 in separated relation with the hingedly connected holding and supporting members.

In the embodiment of the invention as illustrated in Fig. 2, 26 designates generally an ornamental jewelry structure in the form of an ornamental pin, the main portions of which may consist of one or more looped strands 27 suitably arranged to present an ornamental appearance and made up of a metal portion 28 and an ornamental portion 29 closely united therewith to provide a strand of a novel and ornamental character. The ornamental structure may be provided with a pin 30 pivotally mounted thereon, as at 31, and a catch 32 for receiving and holding the free end of the pin. An initial display member 33 is formed integral with or fixedly united to a portion 34 of the ornamental structure and is of a relatively small size as compared with the ornamental structure to provide an initial display means as an adjunct thereto. The initial display member comprises a supporting member 35 having opposed upstanding sides 36, and which may be provided with an opening 37 located substantially centrally thereof and between the upstanding sides 36. A separate supporting plate 38, which may or may not be provided with a central opening 39, is shaped to fit within the upstanding sides 36 and rest upon the supporting member 35. The separate supporting plate 38 is provided upon one side adjacent to a lateral edge thereof with a plurality of raised detents 40 for engagement with recesses 41 formed in the ends of initial members 42 to hold the initial members securely in spaced position upon the supporting plate 38. A holding member 43 is pivotally secured at one end to one end portion of the supporting member 35, as indicated at 44, and has an opening 45 formed therein which may conform substantially in size and location with the openings 37 and 39, when present, in the supporting member and separate supporting plate respectively. The lateral edges of the holding member 43 are adapted to lie partially or wholly within the upstanding sides 36 of the supporting member 35 in the closed positions of the parts, and the holding member 43 is provided with a somewhat resilient end lug 46 adapted to snap over and engage the end 47 of the supporting member 35, which end may be slightly beveled or inclined, to retain the holding member and sup-

porting plate 38 in the closed position.

porting member in closed position. The separate supporting plate 14 is shaped to fit directly within the upstanding walls 11 of the supporting member 10 so that it may be inserted vertically from the top of the holding member in the open position of the parts, and the desired initial members may first be arranged thereon with the recesses 18 suitably arranged with respect to detents 17 carried by the separate supporting plate, and these parts inserted together directly from above into the supporting member. The initial members 19 are so formed as to provide initial portions adapted to be viewed through the opening 23 in the holding member, and end portions receivable between those lateral portions of the holding member and separate supporting plate which are located adjacent to the central opening 23.

The form of ornamental jewelry structure illustrated in Fig. 2 of the drawing comprises an ornamental member 26, in the form of a riding crop, to which may be pivotally secured a pin 27, as at 28, and which may support a suitable catch 29 for engagement with the end portion of the pin 27. An initial display member 8, formed as above described, is secured to or formed integral with the ornamental member 26, being in this instance secured thereto or formed integral therewith along a line located adjacent to the upper edge portion of the initial display member 8. In this, as in the structure previously described, the initial display member is united with the ornamental jewelry structure as an element thereof rather than as constituting the dominant display feature, and is of relatively small size with respect to the ornamental structure to provide an initial display as a subsidiary element of the ornamental structure which does not detract from nor interfere with the ornamental effect produced by the ornamental structure. While the shape of the initial display member is illustrated as of rectangular form, it may assume any other suitable or desired shape dependent upon the arrangement of parts and appearance of the ornamental structure with which it is to be employed. The provision of a separate supporting plate insertable vertically from above within the upstanding side wall of the supporting member permits the employment of initial display members of varying overall contours, such, for example, as diamond shaped, circular, or other regular or irregular shapes.

While the supporting plate 14 is shown herein as being provided with a central opening corresponding substantially in size and shape with that of the holding member 20, the central portion of the separate supporting plate may be made imperforate or formed with striated or other perforations as may best serve to display the initial portions of the initial members.

In forming a jewelry structure of an ornamental character as described and providing an initial display member adapted to be incorporated therein and form a part thereof it is desirable to provide a structure wherein the initial display member may assume various different forms in outline, such as rectangular, oval, diamond shaped and the like. By providing a separate initial supporting plate and constructing the parts to permit vertical insertion of the supporting plate between the upstanding sides of the supporting member as well as the provision of means carried by one face of the supporting plate for properly spacing the initial members any suit-

able or desired shape of initial display member may be employed to conform with the appearance of the jewelry structure as a whole or a part of its design.

Where the supporting member of the initial display member is given a shape other than that shown, the separate supporting plate and holding member are correspondingly shaped and the opposed upstanding walls of the supporting member are formed to receive the separate supporting plate and initial members therebetween, where they are held in position by closing and latching the holding member.

It is to be understood that the ornamental jewelry structure may be in the form of an ornamental pin, brooch, pendant, or any other suitable jewelry structure which presents a novel and ornamental appearance apart from the initial display member.

The initial display member, by reason of the hinged connected supporting and holding plate members and separate supporting plate so formed as to be receivable within or removable from the hinged connected plate members through vertical movement between the upstanding walls of the supporting member, provides a simple and efficient means for the display of initials wherein the initials may be readily inserted or removed and various forms of initials employed without bending or distortion of the initial members and without the careful manipulation necessary for the insertion or removal of initial members in devices of this character as heretofore employed.

What I claim is:—

1. In a device of the character described, an initial display member comprising a supporting plate member and holding plate member hingedly connected together, said holding plate member being provided with a display opening for the display of initial members, said supporting plate member having opposed upstanding side portions, a separate supporting plate insertable within or removable from between the upstanding side portions of the supporting plate member by movement in a direction at right angles to the supporting plate member, initial members carried by said separate supporting plate, and means forming parts of said supporting plate member and holding plate member for holding said initial member and separate supporting plate in display position relative to the opening in said holding plate member when said hingedly connected plate members are in closed position.

2. An initial display structure comprising a supporting member provided with spaced upstanding sides, a holding member pivotally connected to said supporting member and provided with a display opening, means carried by one of said members engaging the other said member in the closed position of the members to releasably secure the members in closed position, an initial supporting plate and initial members receivable between the spaced upstanding sides of said supporting member, and means forming parts of said members for holding the initial supporting plate and initial members in fixed position between said members when the members are secured in closed position.

3. In an initial display structure, a supporting member comprising a base and lateral raised portions forming a recess, a holding member pivotally connected to said supporting member adjacent to one end thereof having a portion fitting within said recess and provided with a display

opening, a separate supporting plate shaped to fit substantially within said recess and provided with means for locating one or more display members relative to the display opening in said holding member, a display member carried by said separate supporting plate, and cooperating means carried by said supporting member and

holding member respectively for securing said holding member in closed position relative to said supporting member and retaining said display member and separate supporting plate in fixed position relative thereto.
